DIRECTION CONTROL DEVICE

Gerhard G. Ohlendorf, Whitsett, Tex.

Application March 17, 1943, Serial No. 479,525

2 Claims. (CL 102-3)

1

My invention relates to bombs of the type which are dropped from aircraft, and has among its objects and advantages the provision of an improved direction control device for changing the path of descent of the bomb to the end that it may be effectively guided to the intended objective.

In the accompanying drawings:

Figure 1 is an elevational view of a bomb in accordance with my invention.

Figure 2 is a nose end view.

Figure 3 is a rear end view.

Figure 4 is a detail view partly in section of an antenna latch.

Figure 5 is a view taken from the position indicated by line 5-5 of Figure 4.

Figure 6 is a fragmentary perspective view of a switch for controlling the circuit which actuates the rudders for restraining the bomb from rotation about its longitudinal axis.

Figure 7 is an enlarged longitudinal sectional view through the tail portion of the bomb.

Figure 8 is a transverse sectional view.

Figure 9 is a view illustrating a motor controlled linkage which operates the rotation controlling rudders.

Figure 10 is a perspective view of the linkage and rudders controlled by the motor of Figure 9.

Figure 11 is a diagrammatic view of the controlled circuits which guide the bomb in flight.

Figure 12 is a diagrammatic view of the control circuit for functionally and selectively influencing the circuit of Figure 11, and

Figure 13 is a fragmentary circuit illustration comprising a part of the circuit of Figure 11.

In the embodiment of the invention selected for illustration, Figure 1 illustrates a bomb 20 which includes a streamlined body 22. The leading end margin of the bomb may be conventional with respect to the exploding charge and firing mechanism. The circuit structure of Figure 11 is housed in the tail margin of the bomb.

More specifically, the bomb 20 includes four airfoils 24 which extend throughout the full length of the bomb, are spaced 90 degrees apart circumferentially of the bomb, and are streamlined when viewed from their outer edges. These airfoils are fixedly related to the bomb. Figures 2 and 3 illustrate the spacing of the airfoils, while Figure 1 illustrates annular airfoils 26 and 28 respectively fixedly related to the forward and rear ends of the airfoils 24. The airfoils 26 and 28 are arranged concentrically of the bomb body 22 and at right angles to its longitudinal axis.

Means for steering or altering the course of

the bomb when released from its carrier, such as an aircraft, comprise four rudders 30 and 32 located at the rear end of the bomb. These rudders normally lie in the planes of the respective airfoils 24, so that two rudders 30 lie in a common plane, while the rudders 32 also lie in a common plane but at right angles to the plane of the rudders 30.

Figures 1 and 7 illustrate the rudders 30 and 32 as being spaced slightly one from the other at their inner ends, and the rudders are pivotally connected at 34 with their respective airfoils 24.

In Figures 7 and 11 the rudders 30 are provided with arms 36 pivotally connected at 38 with rods 40 extending loosely through openings 42 in the bomb shell 44. Both bars are provided with right-angular formations 46 pivotally connected at 48 with a slidably control rod 50. The rod 50 is mounted for axial movement in supports 52, the rod being preferably of noncircular formation as to be restrained from rotation. Thus longitudinal movement of the control rod 50 actuates the rods 40 for imparting simultaneous pivotal movement to the two rudders 30.

The rudders 32 are also provided with arms 54 pivotally connected with rods 56 extending through openings 58 in the shell 44. These rods are pivotally connected at 60 with a control rod 62 also slidably guided in the supports 52 in the same manner as the control rod 50. Accordingly the rudders 32 are also simultaneously actuated about their pivotal axis through longitudinal movement of the control rod 62.

In the gravitational descent of the bomb, the airfoils 24 and the annular airfoils 26 and 28 function as carrying wings. At the same time the course of the bomb may be altered through selective operation of the rudders 30 and 32. For the sake of clearness in the description of the bomb guiding facilities, the rudders 30 are considered as having horizontal positions and the rudders 32 as being vertically positioned. Thus movement of the rudders 30 in one direction from their normal positions will cause the bomb to ascend in its course, while movement of the rudders in the other direction from normal will cause the bomb to descend. Similarly pivotal movement of the rudders 32 in one direction from their normal positions causes the bomb to be deflected to the left, while movement of the rudders in the opposite direction from normal causes a deflection to the right. In the same manner, the course of the bomb may be altered in other directions through a combination movement of the two sets

of rudders, so that the bomb may be accurately directed to a given objective.

In order to maintain effective directional control of the bomb, means are provided for restraining the bomb from rotation about its longitudinal axis. This means comprise two orientation rudders 64 located intermediate the ends of the bomb 20 and spaced 180 degrees apart. In Figures 9, 10 and 11 the orientation rudders 64 are attached to coaxial shafts 66 rotatably mounted in the shell 44 and each provided with an arm 68. These arms are respectively connected with control links 70 pivotally connected together at 72 and with an arm 74 fixed to a rotative gear 76. The arms 68 are so arranged with respect to each other that the shafts 66 and their attached orientation rudders 64 are simultaneously rotated in opposite directions through movement of the links 70, the arm 74 and the gear 76 constituting a crank for imparting movement to the links 70 through rotation of the gear.

Both orientation rudders 64 lie closely adjacent the shell 44. Rotation of the bomb 20 about its longitudinal axis is restrained through the action of the orientation rudders 64. Means are provided for automatically actuating the orientation rudders 64 to restrain the bomb from rotation as any rotation takes place.

In Figure 11 electric motors 78 and 80 of the reversible type are provided for respectively controlling the rudders 30 and 32. These motors respectively drive worms 82 and 84 meshing with worm gears 86 and 88, respectively. The two gear assemblies are identical in construction and operation so that the description of one will apply to both.

Referring to Figure 7 the worm gear 86 is threadedly connected with a screw 90 comprising a part of the control rod 50. This screw extends loosely through openings 92 in brackets 94 fixed to a support 96 comprising a portion of the supports 52. The worm gear 86 is located between the brackets 94 and is restrained from relative axial movement, so that rotation of the worm gear imparts longitudinal motion to the control rod 50.

In Figures 1 through 5, four aerials 98 are employed, which aerials are respectively operatively associated with radio receiver units 100, 102, 104 and 106, see Figure 11.

All the aerials 98 are similar in construction and operation so that the description of one will apply to all. Figure 1 illustrates the aerials in their normal positions before the bomb is released from its carrier. The aerials are pivotally mounted on the annular airfoil 28, the aerials being located 90 degrees apart and arranged to pivot in planes paralleling the longitudinal axis of the bomb.

Figures 4 and 5 illustrate one aerial and its pivotal mount. A bracket 108 is fixed to the annular airfoil 28 and the aerial 98 includes two fixedly related sections 110 and 112, the section 112 being pivotally connected at 114 with the bracket 108. An insulating coupling 116 fixedly connects the sections 110 and 112 in axial alignment, and the aerial tapers uniformly from one end to the other, the larger diameter end terminating with the section 112.

The aerials 98 when viewed according to Figure 1 are arranged in converging relationship with respect to the longitudinal axis of the bomb 20. Such arrangement of the aerials is releasably maintained by latches 118. In Figures 4 and 5 the latch 118 comprises a hook 120 pivot-

ally connected at 122 with lugs 124 fixed to the airfoil 28. A tension spring 126 is connected at one end with the latch member 120 and at its other end with the airfoil 28 to pivot the latch member 120 in a clockwise direction and release the aerial 98. The aerial is positively confined within the hook 120 by a stop 128 so arranged as to prevent accidental disconnection of the aerial from the hook. When the hook member 120 is released, a tension spring 130 pivots the aerial to an operating position, wherein the aerial projects radially and rearwardly from the bomb. This spring has one end attached to the section 112 and its other end fastened to the airfoil 28.

Means for releasably holding the hook member 120 in its latching position of Figure 4 comprises a line or flexible cable 132 passing loosely through an opening 134 in the airfoil 28 and around a grooved sheave 136 mounted on the airfoil. Each hook member 120 is provided with a line 132 all of which are tied to a short line 134 passing loosely through an opening in the airfoil 28 and attached to a ring 136. This ring may be slipped over one of the usual latches associated with bomb racks for maintaining the lines 132 sufficiently taut. As the bomb is released, the ring 136 will of course slip off the latch and permit the springs 130 to pivot the aerials to their operating positions.

In Figures 11 and 13, the control bar 50 includes a switch member 138 provided with insulating contacts 140 and 142 arranged for selective engagement with switch elements 144 and 146, respectively. The drawings illustrate the switch member 138 in a normal position, at which time both elements 144 and 146 are in closed positions. These elements respectively carry contacts 148 and 150 normally engaging contacts 152 and 154, respectively. The contact 152 is electrically connected with a wire 156, while the contact 154 is electrically connected with a wire 158.

A switch arm 160 is also provided for the control rod 62, this arm being provided with insulating contacts 162 and 164 selectively engageable with switch elements 166 and 168, respectively. These switch elements are provided with contacts 170 and 172 normally engaging contacts 174 and 176, respectively. Wires 178 and 180 are respectively connected with the contacts 174 and 176. The two switch assemblies 182 and 184 associated with the switch arms 138 and 160, respectively are identical, each being opened through axial movement of the respective control rods 50 and 62.

For bomb controlling purposes, the radio receiver units 100 and 102 control the left and right deflection of the bomb, while the receiver units 104 and 106 respectively control the upward and downward deflection. Relays 186, 188, 190 and 192 are respectively operatively associated with the radio receiver units 100, 102, 104 and 106, respectively, as through the medium of suitable circuit wires 194.

Three switches 196, 198 and 200 are controlled by the relay 186. These switches respectively comprise fixed contacts 202, 204 and 206, which in turn are respectively associated with contacts 208, 210 and 212. Control levers 214 are respectively connected with the contacts 208, 210 and 212; having a common pivot 216 and connected with the insulated part 218 of an armature 220 controlled by the relay 186.

A tension spring 222 is connected with the armature 220 to bias the latter away from the relay 186 for closing the switches 196, 198 and 200.

However, upon a predetermined degree of energization of the relay 186, the armature 220 is attracted to the relay for opening the switches 196, 198 and 200. Such energization of the relay 186 is controlled by the radio receiver unit 100. The wire 178 is electrically connected with the contact 204, while the switch element 168 is electrically connected with a wire 224 electrically connected with the contact 202.

An armature 226 is operatively associated with the relay 188, which armature includes an insulating body 228 connected with levers 230 mounted on a common pivot 232. These levers are respectively connected with contacts 234, 236 and 238 of switches 240, 242 and 244, respectively. Associated with the movable contacts 234, 236 and 238 are fixed contacts 246, 248 and 250, respectively. A wire 252 electrically connects the contact 206 of the switch 200 with the contact 246 of the switch 240. The armature 226 is biased by a spring 253 in the same manner as the armature 220. A wire 254 electrically connects the contact 248 of the switch 242 with the switch element 166, while the wire 180 electrically connects the contact 250 of the switch 244 with the contact 176 in the switch 184.

Associated with the relay 190 are three switches 256, 258 and 260. These switches respectively include fixed contacts 262, 264 and 266. Movable contacts 268, 270 and 272 are respectively associated with the contacts 262, 264 and 266. The contacts 268 through 272 are respectively connected with levers 274 mounted on a common pivot 276 and connected with the insulating body 278 of an armature 280 controlled by the relay 190, the latter being in turn controlled by the radio receiver unit 104. A spring 282 biases the armature 280 from the relay 190 upon predetermined deenergization thereof for closing the switches 256 through 260.

The wire 156 electrically connects the contact 266 in the switch 260 with the contact 152 in the switch 182. A wire 284 electrically connects the contact 264 in the switch 258 with the switch element 146 in the switch 182.

Three switches 286, 288 and 290 are operatively associated with the relay 192, the latter being controlled by the radio receiver unit 106. The switches 286 through 290 respectively include fixed contacts 292, 294 and 296, the contact 292 being electrically connected with the contact 262 by wire 298. Movable contacts 300, 302 and 304 are respectively associated with the fixed contacts 292, 294 and 296, the contacts 300 through 304 being respectively mounted on levers 306 having a common pivot 308 and operatively connected with an insulating body 310 of an armature 312 controlled by the relay 192. This armature is biased by a spring 314 to close the switches 286, 288 and 290 upon predetermined deenergization of the relay 192. A wire 316 electrically connects the contact 294 of the switch 288 with the switch element 144 of the switch 182, and the contact 296 of the switch 290 is electrically connected with the wire 158 leading to the contact 154 of the switch 182.

Current is supplied to the radio receiver units 100 through 106 by a battery 316 to which a lead 318 is connected and electrically connected with the respective circuits of the radio receiver units 100 through 106. A second wire 320 is also electrically connected with the radio receiver circuits and with a switch element 322 of a control switch 324 which, when closed, supplies current to the radio receiver units 100 through 106. The

switch element 322 is biased to a closed position by a spring 326 for engagement with a contact 328 in the switch 324, this contact being electrically connected with the battery 316 by a wire 330.

Normally the switch 324 is maintained in an open position, this switch being closed only as the bomb is released from the aircraft. Means for maintaining the switch in an open position comprises a line or cable 332 attached to a ring 334 which may be fastened in the same manner as the ring 136 to hold the switch 324 open until the bomb is released.

The motors 78 and 80 receive operating current from a battery 336, this battery being connected with a wire 338. The other side of the battery is connected with a control switch 342 comprising a switch element 344 normally held in an open position by a line 346 attached to the ring 334. The switch 342 includes a contact 348 engageable by the element 344, the latter being biased to a closed position by a spring 350 when the ring 334 is released, so that the switches 342 and 324 are automatically and simultaneously closed upon release of the bomb from its bomb rack. The contact 348 is electrically connected with a line wire 352, the wire 338 constituting the second line wire from the battery 336. The switch 342 also controls the orientation circuit 354 of Figure 11, this circuit controlling the operation of the orientation rudders 64.

In Figure 13 the contact 208 of the switch 196 is connected with a wire 356 lugged to the line wire 352, while the contact 210 of the switch 198 is connected with a wire 358 electrically connected with the contact 238 of the switch 244, as by a wire 360. A wire 362 electrically connects the contact 270 of the switch 258 with the line wire 352, and a wire 364 electrically connects the contact 272 of the switch 260 with the contact 304 of the switch 290. A wire 366 connects the contact 234 of the switch 240 with the line wire 338. The corresponding contact 300 in the switch 286 is also electrically connected with the line wire 338 by a wire 368.

The armature of the motor 80 is electrically connected with the wires 224 and 254 as at 370 and 372, respectively, while the motor field is electrically connected with wires 374 and 376. The wire 374 is electrically connected with the wire 360, while the wire 376 is lugged to the line wire 338. In the same manner, the armature of the motor 78 is electrically connected with the wires 284 and 316, as at 378 and 380, respectively. Wires 382 and 384 are electrically connected with the field of the motor 78, the wire 382 being electrically connected with the contact 304 of the switch 290. The wire 384 is electrically connected with the line wire 338.

The radio receiver units 100 through 106 are subjected to the controlling influence of the control circuit 386 of Figure 12. This circuit includes radio transmitters 388, 390, 392 and 394 for respectively controlling the radio receiver units 100 through 106. While the circuit of Figures 11 and 13 are incorporated in the bomb, the control circuit of Figure 12 is incorporated in the aircraft from which the bomb is released, as well as in other aircrafts which may be employed as a supplemental aid to the bomb releasing aircraft for directing the bomb to its target. In many cases, the bomber alone can amply handle the situation with respect to directive control of the bomb, but there may be cases in which it is advisable and necessary to employ the aid of an-

other aircraft equipped with a control circuit such as that illustrated in Figure 12 to more effectively direct the bomb to its objective, as well as to explode the bomb.

The radio receiver units 100 through 106 are respectively tuned to the transmitting frequencies of the transmitters 388 through 394, respectively. In other words, the radio receiver unit 100 is functionally responsive to the frequency characteristics of the transmitter 388 only, which is also true of the radio receiver units 102, 104 and 106 with respect to the transmitting frequency characteristics of the transmitters 390, 392 and 394, respectively.

Aerials 396 are respectively provided for the transmitters 388 through 394.

The transmitters 388 through 394 are functionally controlled by a master switch 398. This master switch includes four secondary switches 400, 402, 404 and 406 operatively connected with the transmitters 388, 390, 392 and 394, respectively. Each of the switches 400 through 406 comprises a fixed contact 408 and a movable contact 410, these contacts being electrically connected with their respective transmitter, as at 412 and 414, respectively. The switch 398 also includes a control rod or switch actuator 416 which is preferably mounted for pivotal movement for selectively actuating the switches 400 through 406. The secondary switches are grouped about the control rod 416 so that the latter may be manipulated in different directions for selective engagement with the movable contacts 410. These contacts are preferably so arranged that left, right, up and down movements of the control rod 416 closes the circuit through their respective transmitters for correspondingly imparting left, right, up or down deflection of the bomb.

In addition, the movable contacts 410 are so arranged that the control rod 416 may simultaneously selectively engage two movable contacts 410 to modify the deflection of the bomb from true left, right, up and down deflections. More specifically, the control rod 416 may be brought into engagement with the movable contacts 410 of the secondary switches 400 and 404 to close the circuits through the left and up directional transmitters 388 and 392, which in turn results in bringing the two radio receiver units 100 and 104 into play for imparting a combination left and upward deflection to the bomb. Movement of the control rod 416 into engagement with the movable contacts 410 of the secondary switches 404 and 402 similarly influences the radio receiver units 104 and 102 to cause right and upward deflection of the bomb.

Right and down deflection of the bomb is determined by bringing the control rod 416 into engagement with the movable contacts 410 of the secondary switches 402 and 406, while down and left deflection of the bomb is determined by engagement between the control rod 416 and the movable contacts of the secondary switches 400 and 408.

A signal transmitted by the transmitter 388 through closing of the secondary switch 400 influences the radio receiver unit 100 only, which results in a reduction of the plate current and deenergizes the relay 186 in such an amount as to render the spring 222 effective for closing all the switches 196, 198 and 200. When the switches 196 and 198 are closed, the circuit through the motor is closed as follows: from the battery 336 to wire 338, wire 376 to the motor field, wire 374 to wire 358, through the switch 188 and to wire

178, through contacts 174 and 170 and to the wire 254, wire 372 to the motor armature and to wire 370 connected with the wire 224 which connects with the switch 196, and from this switch through wires 356 and 352 back to the battery. As the motor is energized, rotation of the worm 84 imparts rotary motion to its worm gear 88 and longitudinal movement to the control rod 62.

The worm gear 88 is rotated in a direction which causes the control rod 62 to move to the left when viewing Figures 11 and 13. Such movement of the control rod pivots the rudders 32 in a direction which deflects the bomb to the left. So long as the secondary switch 400 is maintained in a closed condition by the control rod 416, the motor 80 will continue its operation and the control rod 62 will also continue its movement to the left. However, the motor 80 may be deenergized at will through opening of the secondary switch 400. If the secondary switch 400 is maintained in a closed condition for a given length of time, the control rod 62 moves sufficiently far to bring the insulating contact 162 into engagement with the switch element 168 to break the motor circuit.

To deflect the bomb to the right, the secondary switch 402 is closed by the control rod 416, which influences the radio receiver unit 102 to deenergize the relay 188 in an amount which permits the spring 254 to retract the armature 226 and close all the switches 240, 242 and 244. At this time, the motor circuit is closed as follows: from the battery 336 to the wire 338, wire 376 through the motor field and to wire 374, through switch 244 and to the wire 180, through contacts 176 and 172 and to the motor armature in a reverse direction, and then the wire 372, wire 254 through the switch 242 and to the wire 352 back to the battery 336.

Upon closing of the circuit through the motor 80 through the medium of the secondary switch 402, the motor is reversed and the control rod 62 is caused to move to the right when viewing Figures 11 and 13. This movement of the control rod 62 continues or may be controlled in the same manner as previously described with respect to its movement to the left.

To deflect the bomb upwardly, the secondary switch 404 is closed to influence the radio receiver unit 104 and deenergize the relay 190 in an amount which permits retraction of the armature 220 by the spring 282. Such retraction of the armature causes all the switches 256, 258 and 260 to close.

Upon closing of the latter mentioned switches the circuit of the motor 78 is closed in the following manner: from the battery 336 to wires 338 and 384, through the field of the motor 78 and to the wire 382, wire 364 and through the switch 260, wire 156, contacts 152 and 148 and to the wire 316, wire 380 to the armature of this motor and from the armature to the wires 378 and 284, switch 258 and to the wire 352 back to the battery 336. This will cause the motor 78 to operate and turn the worm 82 for imparting rotation to the worm gear 88 in such direction as to move the control rod 50 to the left, as when viewing Figures 11 and 13. Such movement of the control rod 50 pivots the rudders 30 to cause upward deflection of the bomb. With respect to deenergization of the motor 78, this is identical with that previously described in connection with the motor 80.

To impart downward deflection to the bomb, the secondary switch 406 is closed which in-

fluences the radio receiver unit 106 to deenergize the relay 192 in an amount which permits retraction of the armature 312 by the spring 314. Retraction of the armature 312 causes all the switches 288, 288 and 290 to close. At this time, the circuit is closed through the motor 78 as follows: from the battery 336 to wires 338 and 384, through the field of the motor and to the wire 382, switch 290 and the wire 158, contacts 154 and 150, wire 378 and through the armature in a reverse direction to the wire 380 and to the wire 316 which leads to the switch 288, and from the switch 288 back to the battery through the medium of the wire 352. Reversed operation of the motor 78 causes the control bar 50 to move to the right when viewing Figures 11 and 13, which pivots the rudders 30 to impart downward deflection to the bomb. Deenergization of the motor 78 under these conditions is also identical with that previously described in connection with the motor 80.

When the secondary switches 400 and 404 are simultaneously closed by the control rod 416, both motors 78 and 80 are energized, in the same manner as when energized individually through selective closing of these secondary switches, for actuating both sets of rudders 30 and 32 to cause deflection of the bomb to the left and up. Simultaneous closing of the secondary switches 404 and 402 also energizes both motors 78 and 80, identically with individual energization thereof, to move both sets of rudders 30 and 32 to cause the bomb to be deflected upwardly and to the right. Simultaneous closing of the secondary switches 402 and 406 and 408 and 400 cause actuation of the rudders 30 and 32 to deflect the bomb downwardly and to the right and downwardly and to the left, respectively.

Rotation of the bomb about its longitudinal axis is controlled by the orientation circuit 354. This circuit includes a reversible motor 418 which drives a worm 420 meshing with the worm gear 76. The orientation rudders 64 rotate about a common axis arranged radially with respect to the longitudinal axis of the bomb 20. The bomb may be caused to rotate about its longitudinal axis through adjustment of the orientation rudders to such angular positions as to cause the latter to function with a screw or rotary action with respect to the bomb.

Included in the orientation circuit 354 is a gyroscope mechanism 422 comprising gyroscope units 424. The units 424 include a frame 426. The frame 426 is mounted inside a ring 428 and is pivotally supported therein for movement about an axis 430. The frame 426 is provided with two gyro rotors 432 which rotate about axes 434. The axes 434 comprise shafts rotatably journaled in the frame 426, these shafts being arranged at an angle of 90 degrees to each other, and each shaft is arranged at an angle of 45 degrees to the axis 430. Each axis or shaft 434 is driven by a motor 436, these motors being electrically connected with the line wires 338 and 352.

The ring 428 is supported in a half circular yoke 438 for pivotal movement about an axis 440, this axis being at right angles to the axis 430. Light tensioned springs 442 are connected with the ring 428 and with a projection 444 fixed to the yoke 438 to yieldingly bias the ring 428 to a right angular position with respect to the yoke.

The yoke 438 is provided with a shaft 446 arranged coaxially with the ring 428 when the parts are in the relative positions of Figure 11, this shaft being rotatably supported in a suitable

bearing means 448. This shaft is fixedly connected with a cam member 450 provided with an arm 452 constituting a switch element, the cam and the arm being best illustrated in Figure 6. The arm 452 is formed of insulating material and includes a right angular part 454 upon which are fixedly mounted two conductors 456 and 458 provided with contacts 460 and 462, respectively. In Figure 11, a wire 464 electrically connects the contact 460 with the armature of the motor 418, a second wire 466 leading from the armature to the contact 462. The contact 460 is arranged for selective engagement with contacts 468 and 470 through movement of the arm 452, as the latter is rotated with the shaft 446. The contact 462 is arranged for selective engagement with contacts 472 and 474 through the same operation of the arm 452.

In Figure 6, the contacts 468 and 472 are mounted on a support 476, while the contacts 470 and 474 are mounted on a second support 478. These two supports are spaced one from the other to provide accommodation for the right angular part 454 of the arm 452, there being sufficient space to permit a slight amount of relative movement between the part 454 and the two supports.

The supports 476 and 478 comprise a fixed part with an upstanding arm 480 pivotally mounted on a pin 482 threaded into a support 484 fixedly secured in any suitable manner inside the bomb. The shaft 446 is coaxial with the pin 482, and the upstanding member 480 lies against the support 484 and is pressed thereagainst by a compression spring 486 interposed between the head of the pin 482 and the member. This member depends from the pin 482 and is provided with a weight 488 which balances the member in its upright position.

A weight 490 depends from the shaft 446 to maintain the arm 452 in an upright position as the bomb is released. The bomb is positioned in the rack and released therefrom with the arm 452 in this position. With the arm 452 positioned vertically, the axis 440 which pivotally supports the ring 428 of the gyroscope mechanism 422 is also in a vertical position.

A wire 492, see Figure 11, connects with the wire 338 and leads to the field of the motor 418, the other wire 494 of the field being electrically connected with two fixed contacts 496 and 498. The contacts 496 and 498 are incorporated in switches 500 and 502, respectively, these switches being respectively provided with movable contacts 504 and 506 normally engaging the contacts 496 and 498, respectively.

The movable contact 504 is connected with a wire 508 leading to a switch 510 and connected with a fixed contact 512 in that switch. The corresponding contact 506 in the switch 502 is connected with a wire 514 leading to a switch 516 and is connected with a fixed contact 518 in that switch. A movable contact 520 is normally electrically engaged with the contact 512 and is connected with a wire 522 leading to the contact 468. Similarly the contact 518 is normally engaged with a movable contact 524, the latter being connected with a wire 527 leading to the contact 474. The contact 470 is electrically connected with the wire 352, which is also true of the contact 472.

A resistance 530 bridges the wires 508 and 522, while the resistance 532 bridges the wires 514 and 527. The cam 450 includes projections 526 and 528 respectively engageable with the contacts 520 and 524 to open the switches 510 and 516 upon

a predetermined rotation of the bomb relatively to the gyroscope mechanism 422. The member 480 of Figure 6 is so balanced as to turn with the bomb as it rotates about its longitudinal axis, but the spring 486 is so loaded as to provide little resistance to rotation of the member about the pin 482. The gyroscope mechanism 422 maintains the axis 430 horizontally in all positions of the bomb, so that the arm 452 is always arranged at right angles to the axis 430 since it is fixedly related to the yoke 438. Thus the member 480 is caused to oscillate with the rotary movement of the bomb about its longitudinal axis, and relatively to the arm 452.

In employing two gyroscope units 424 arranged in the manner of Figure 11, the gyroscope unit 422 is highly efficient, since at all times at least one axis 434 is arranged at an angle to the axis of the shaft 446, thereby preventing the gyroscope mechanism from becoming inoperative for its intended function, as in the case of a single gyroscope mechanism wherein the axis of the gyroscope rotor might be positioned in parallelism with an axis corresponding to that of the shaft 446.

After release of the bomb, rotation of the bomb about its longitudinal axis in either direction shifts the member 480 relatively to the arm 452, so that the contacts 468 and 472 on one side and the contacts 470 and 474 on the other side are shifted relatively to the stationary contacts 480 and 482. Since the switch 342 is closed immediately upon release of the bomb, current is supplied to the gyroscope motors 436 so that these units are set in operation immediately upon release of the bomb.

Should the bomb rotate in one direction sufficiently far to bring the contacts 460 and 462 into engagement with the contacts 468 and 472, the circuit through the motor 418 is closed as follows: from line wire 338 to wire 492 and the field of the motor 418, from which the current flows to the wire 494, contacts 498 and 504, the wire 508 and contacts 512 and 520, wire 522, contacts 468 and 480, wire 484 to the armature of the motor and then to wire 466 and through the contacts 462 and 472, the latter being electrically connected with the line wire 352.

When the motor circuit is closed in the foregoing manner, the worm 420 is rotated to impart rotation to the worm gear 76 which in turn actuates the links 70 and rotates the orientation rudders 64 simultaneously in opposite directions to bring the bomb back toward its normal position. Excessive rotation of the gear 76 is controlled in either direction by the limit switches 500 and 502.

Rotation of the bomb about its longitudinal axis reversely of that previously described brings the contacts 460 and 462 into engagement with the contacts 470 and 474, so that the circuit will be closed through the motor in the following order: from line wire 338 to wire 492, the field of the motor and wire 494, the contacts 498 and 506, wire 514, contacts 518 and 524, wire 527, contacts 474 and 482, wire 466 to the armature of the motor in a reverse direction and then to the wire 464, and the contacts 460 and 470, the latter being connected with the line wire 352. Such energization of the motor 418 imparts reverse rotation to the gear 76, so that the orientation rudders 64 are pivoted in the reverse direction from that previously described.

It will thus be seen that rotation of the bomb about its longitudinal axis is controlled in either

direction, any unintended rotation of the bomb being limited to slight oscillation within the operating relationships between the two sets of contacts 468 and 472 and the contacts 460 and 462 and the latter and the two contacts 470 and 474.

The switches 510 and 516 have fixed positions in the bomb, so that rotation of the bomb causes relative shifting of the movable contacts 520 and 524 with respect to the cam projections 526 and 528, respectively. With respect to the cam projection 528, the switch 510 remains closed until after contact has been established between the contacts 460 and 462 and the two contacts 470 and 474. Continued rotation of the bomb after such contact has been established shifts the movable contact 520 sufficiently far with respect to the cam projection 526 as to cause the latter to move the contact 520 out of engagement with the contact 512. As the orientation rudders become effective for imparting reverse rotation to the bomb, the contacts 460 and 462 are brought into engagement with the contacts 468 and 472, which reverses the motor, and adjusts the orientation rudders 64 back to normal and slightly beyond so as to balance the righting adjustment of the bomb.

Since the switch 510 was in an open condition during engagement between the contacts 460 and 462 and their contacts 468 and 472, the speed of the motor was reduced because of the resistance 530 so as to operate the motor at a desirable low speed to dampen the turning movement of the bomb as it approaches its normal position. Should the bomb be turned beyond its normal position, the switch 510 closes as the bomb reaches its normal position, which again shunts the resistance 530 out of the motor circuit so that the orientation rudders 64 may be more speedily adjusted to resist continued rotation of the bomb beyond normal. The switch 516 functions identically with the switch 510, but the two switches are alternately brought into play so that the bomb is oriented toward normal in the same manner in either direction.

Referring to Figure 7, a cup 534 is attached to the tail end of the bomb 20 and is located between the inner ends of the rudders 30 and 32. This cup is open at its rear end and is supplied with an illuminating flare material 536, which may be illuminated after release of the bomb to provide an observable pilot which aids the operator in visually determining the position of the bomb, particularly under operating conditions where the bomb must travel to such a distance that the bomb alone is not readily visible to the operator.

The material 536 may be ignited at will. Means for igniting the material comprises a control or spring biased push button 538, see Figure 12, which includes a plunger 540 arranged to engage an insulating body 542 to which movable contacts 544 and 546 are attached. The contacts 544 and 546 are respectively movable into engagement with contacts 548 and 550, respectively. The contact 544 is connected with a wire 552 electrically connected with the wire 554 leading from the contact 410 to the transmitter 394. A wire 558 leads from the contact 548 to the wire 558 which leads from the contact 408 to the transmitter 394. The contacts 546 and 550 are respectively electrically connected with the wires 414 and 412 leading to the transmitter 392. Thus the circuits of the transmitters 392 and 394 may be simultaneously closed through actuation of the

plunger 540. The material 536 is ignited at will through actuation of the plunger 540. Means for igniting the material 536 comprises a percussion cap 560, see Figure 13, suitably buried in the flare material 536. This cap may be struck at will by an armature 562 associated with a solenoid 564. A spring 566 yieldingly holds the armature 562 in its retracted position, and the armature is caused to strike the cap 560 upon energization of the solenoid 564.

In Figure 13 a high resistance relay 568 is electrically connected with the line wire 388 by a wire 570. The second wire 572 of the relay is lugged to a wire 574 which leads from the movable contact 268 of the switch 256, and to a low resistance relay 576. Associated with the relay 568 is a switch 578 which includes an armature 580 adapted to be attracted by the relay 568 when the latter is energized. The switch 578 includes a contact 582 which may be moved into engagement with a fixed contact 584 through movement of the armature 580. A wire 586 connects the contact 584 with the wire 352, and a resistance 588 is connected across the wires 586 and 572.

Before the bomb is released from the aircraft, the switches 324 and 342 are held in open positions, and the switch 578 also remains in an open position. Upon release of the bomb the switches 324 and 342 close, the closing of the switch 324 energizing the radio receiver units 100 through 108. Closing of the circuits through the radio receiver units cause energization of the relays 186 through 192 for attracting all the armatures 220, 226, 280 and 312 to the positions of Figure 13. Upon separation of the contacts 268 and 300 from their respective contacts 282 and 292, the relay 568 is energized and the switch 578 is caused to close and remain in a closed position by reason of a latch 590. The relay 568 is caused to energize as follows: from the battery 336 through the wires 388 and 570 and to the relay 568, from the relay through the wire 572 through the resistance 588, the wire 566 and back to the line wire 352. Prior to energization of the relays 190 and 192, the switches 256 and 286 were closed thereby short circuiting the relay 568 to prevent closing of the switch 578. With the switches 256 and 286 in their closed positions, the current would flow as follows: from the battery 336 to the wire 352, the wire 586 and the resistance 588 to the wire 572, wire 574, switch 256, wire 298, switch 286, wires 368 and 388 to the battery 336.

Electrically connected with the armature 580 is a wire 592 which leads to the relay 576, this relay being electrically connected with the wire 574. With the switch 578 in a closed position, current may flow from the wire 352 through the wire 586, contacts 584 and 582, the armature 580, wire 592, the relay 576 and through the switch 256, wire 298, switch 286, the wire 368 to the line wire 388, assuming that both radio receiver units 104 and 108 have been influenced through manipulation of the plunger 540, of Figure 12, for bringing the two contacts 544 and 546 into circuit closing engagement with the contacts 550 and 548, respectively. Energization of the relay 576 attracts an armature 594 for bringing its contact 596 into engagement with a fixed contact 598 wired at 600 to the solenoid 564, the armature 594 being electrically connected with the line wire 388. Such movement of the armature 594 closes the circuit through the solenoid 564 since the latter is electrically connected with the line wire 352 and causes the armature 562 to strike the cap

536 and ignite the flare material. Closing of the switch 578 connects the relays 568 and 576 in series, but since the relay 568 is of a high resistance, insufficient current will be delivered to the relay 576 to influence the armature 594, the relay 576 being of low resistance. Thus the igniting of the flare material 536 is controlled at will.

Means is provided for firing the bomb at will. Such means includes a solenoid 602 for actuating a firing element or armature 604 arranged to strike a percussion cap or other firing means 606 upon energization of the solenoid 602. The solenoid 602 is connected in a control circuit 608 which includes a high resistance relay 610 and a low resistance relay 612 corresponding to the relays 568 and 576, respectively. The solenoid 602 is identical with the solenoid 564 so far as its electrical circuit and operation are concerned, with the exception that the circuit 608 is electrically related to the two radio receiver units 100 and 102, the latter being functionally controlled for bomb firing purposes through the medium of a plunger 614, see Figure 12. The plunger 614 is spring biased to a normal position and includes a pressure button 616. An insulating body 618 is connected with movable contacts 620 and 622 arranged to be simultaneously and respectively moved into engagement with fixed contacts 624 and 626. A wire 628 electrically connects the contact 620 with the transmitter 388, a wire 630 electrically connecting the contact 624 with the transmitter 388. Wires 632 and 634 respectively connect the contacts 622 and 626 with the transmitter 390. Thus the transmitters 388 and 390 are controlled through manipulation of the plunger 614 in the same manner as the transmitters 392 and 394 with respect to the plunger 540.

It will thus be seen that I have provided a bomb which may be effectively controlled from a distant position so that the bomb may be effectively and accurately guided to the target. The bomb also embodies means whereby the pilot light enables the operator to trace the bomb under conditions wherein the bomb is not otherwise readily visible. The bomb also may be exploded at will. The circuit of Figure 12 embodies simple controls wherein applied pressure to the plungers 540 and 614 respectively brings the flare and exploding facilities into operation.

The bomb is effectively restrained from objectionable rotation about its longitudinal axis. In cases where the bomb rotates in either direction from normal, the bomb is reversely rotated back toward normal in an effective and gentle manner so as to eliminate objectionable rapid adjustments which naturally render the bomb adjustment erratic.

In view of the fact that bombs of this type are usually dropped from a considerable height, the longitudinal axis of the bomb does not necessarily at any time lie horizontally. Accordingly, any reference to the vertical positions of the arm 452 and member 480 of Figure 6 does not imply true vertical positions of these elements at all times, but denotes a perpendicular position with respect to a plane common to the longitudinal axis of the bomb and the axis 430.

The aerials 98 when in the positions of Figures 1, 2 and 3, are closely nested about the bomb 20 so as to provide a compact arrangement, one which does not interfere with the bomb racks, or handling of the bomb both with respect to storage and loading.

The airfoils 24, 26 and 28 are efficient in operation and yet so arranged as not to lend objectionable bulk to the bomb. The bomb as a whole is of generally cylindrical contour and is devoid of objectionable projections, and is easily handled. Obviously the bomb has its center of gravity so located as to facilitate proper endwise travel of the bomb, the airfoils 24 and 26 having carrying functions which facilitate horizontal movement and deflection of the bomb with respect to impinging air pressures effective on the airfoils. The airfoil 28 and the rudders 30 and 32 perform an efficient steering function, both with respect to travel of the bomb with the rudders in neutral positions and when adjusted centrally or in combination to bomb deflecting purposes.

The switch 398 of Figure 12 is so devised as to facilitate selective manipulation of the control rod 418, which rod is so arranged with respect to the secondary switches 400 through 406 as to be located within the surrounding arrangement of the secondary switches to the end that the control rod is easily shifted to switch selecting positions, both with respect to the secondary switches singly or in combination.

While practically all bombs released from aircrafts drop with a nonrotational movement, there are a few cases in which the bomb releasing mechanism might impart some rotational movement to the bomb. In cases where a considerable rotational movement might be imparted to the bomb as it is released, such movement does not impair the functioning of the steering mechanism. Even though the bomb should be turned one or more complete turns, no harm is done to the structure of Figure 6, notwithstanding the fact that the arm 452 is maintained in an unvariable given position. While this arm is confined between the portions 476 and 478 of the member 480, the latter member is rotatably mounted on the pin 482, so that the member may be rotated without obstruction from the pin or the bearing 484. The spring 486 offers no objectionable resistance in this connection. The gyroscope mechanism 422 will always remain in a position where its axis 430 is parallel to the horizontal.

Assuming a condition wherein the bomb is released in its normal position but is rotated slightly upon its release, for example, an eighth of a turn from normal in either direction, the motor 418 is immediately energized for adjusting the orientation rudders 64 to positions for imparting righting movement to the bomb. The rudders 64 are adjusted rapidly to this position. As the bomb starts its righting movement, the rudders are slowly pivoted toward normal positions and beyond to dampen righting movement of the bomb. The bomb will turn slightly beyond normal, at which time the rudders 64 are again quickly adjusted to impart a righting movement to the bomb, the latter turning beyond normal but in a lesser degree. Thus the bomb oscillates in a progressively decreasing amount until it becomes stable, characterized by slight oscillatory movement of the bomb.

The fast and slow adjusting movements of the orientation rudders 64 respectively take place as the resistances 530 and 532 are respectively outside and within the motor circuit effective at that time, the resistances being respectively in the motor circuit during turning movement of the bomb toward normal from either position.

Assuming a condition wherein the bomb is released in a normal position but is rotated in a considerable degree upon its release, for exam-

ple, a half turn, the motor is immediately energized to adjust the orientation rudders 64 to righting position. As the bomb turns in a righting direction, the rudders 64 are moved slowly to normal and beyond, which arrests righting movement of the bomb before it returns to normal, and imparts turning movement to the bomb away from normal, but the rudders are then rapidly adjusted to positions for turning the bomb toward normal. This oscillatory movement of the bomb continues, with the bomb progressively advancing to normal, until the bomb finally reaches its stable condition.

In a condition where the bomb is caused to spin upon its release, which is an exception, the orientation rudders 64 are immediately rendered effective for retarding the spin.

Should the bomb be stopped in its rotation three-quarters of a turn beyond normal, the rudders are set to turn the bomb away from normal. As the bomb starts to turn away from normal, the rudders are adjusted rapidly to righting positions. As the bomb turns toward normal, the rudders are slowly adjusted toward normal and beyond. As the bomb again turns away from normal, the rudders are again adjusted rapidly to the other positions. This action continues as previously described in connection with the half turn situation. In cases where the bomb stops at a half turn beyond normal after a spin, the bomb is righted in the same manner as previously described in connection with the half turn situation.

In connection with the flare features, such a means may be employed for illumination purposes, particularly when positioned in advance of the bomb. Obviously such a means may be connected in series with the flare igniting circuit, or substituted in lieu of the flare feature.

In Figures 11 and 13, the switches actuated by the relays 188 through 192 are closed when the switches 324 and 342 are open, as before the bomb is released.

Without further elaboration, the foregoing will so fully explain my invention, that others may, by applying current knowledge, readily adapt the same for use under various conditions of service.

I claim:

1. In combination, an aerial bomb having airfoils extending the length thereof and circumferentially spaced thereabout, a first rudder means at the rear end of the bomb for controlling the flight of the same in one plane, a second rudder means at right angles to said first rudder means and positioned at the rear end of the bomb for controlling the flight of the same in a plane normal to said first mentioned plane, a first reciprocating means attached to said first rudder means for actuating the same, a second reciprocating means attached to said second rudder means for actuating the same, a first and a second reversible electric motor, mechanical means interconnecting said reversible electric motors with said respective reciprocating means for actuating the same, a source of electrical energy carried by said bomb, a first pair of radio receiver units carried by said bomb for controlling said first reversible electric motor, a second pair of radio receiver units carried by said bomb for controlling said second reversible electric motor, each of said radio receiver units being responsive respectively to radio impulses of different predetermined radio frequencies, an electric relay mechanism controlled by each of said radio receiver units, a pair of said relay mechanisms

interposed between said source of energy and each of said reversible motors, respectively, each said relay mechanism of a pair controlling the energization and a direction of rotation of one of said reversible motors, an illuminating flare device attached to said aerial bomb whereby flight of the same may be observed, electromagnetic igniting means for causing ignition of said flare device, electric circuit means associated with said electromagnetic igniting means and with a pair of said relay mechanisms whereby simultaneous actuation of the same by a pair of radio receiver units upon simultaneous receipt of radio impulses by the same will activate said electric circuit means to operate said electromagnetic igniting means. 15

2. The combination as set forth in claim 1 and a pair of orientation rudders pivoted diametrically on said bomb normal to the longitudinal axis thereof and intermediate the ends thereof for controlling rotation in azimuth of said bomb about its longitudinal axis, linkage means for simultaneously rotating said orientation rudders in opposite directions to control rotation in azimuth of said bomb about its longitudinal axis, a 25 reversible electric motor, mechanical means connecting the same with said linkage means for controlling operation of the same, circuit means connecting said motor with the source of electrical energy, a yoke pivoted to said bomb, gyro- 30

scopic means carried by said yoke for stabilizing the same in azimuth, switch means interposed between the source of energy and said reversible electric motor for controlling the flow and direction to same, and cam means operated by said yoke for actuating said switch means upon rotation of said bomb in azimuth about its longitudinal axis. 5

GERHARD G. OHLENDORF.
